UNITED STATES PATENT OFFICE.

JULIUS G. KERNEK AND HENRY E. KERNEK, OF POPLAR BLUFF, MISSOURI.

WAGON-STANDARD.

SPECIFICATION forming part of Letters Patent No. 586,440, dated July 13, 1897.

Application filed April 22, 1896. Serial No. 588,543. (No model.)

To all whom it may concern:

Be it known that we, JULIUS G. KERNEK and HENRY E. KERNEK, of the city of Poplar Bluff, Butler county, State of Missouri, have 5 invented certain new and useful Improvements in an Adjustable Farm-Wagon Standard, of which the following is a full, clear, and exact description, reference being had to the accompanying drawings, forming a part 10 hereof.

Our invention relates to an improved extension wagon-stake; and it consists in the novel construction, combination, and arrangement of parts hereinafter described and claimed.

15 In the drawings, Figure 1 is a perspective of the end of a wagon-bolster, showing our improved extension-stake attached thereto and the position of the stake relative to the box, a part of the box being broken away to economize 20 space and the upward motion of the extension-piece being indicated by dotted lines. Fig. 2 is transverse sectional view of the part shown in Fig. 1, and Fig. 3 is a longitudinal sectional view.

25 Referring to the drawings by numerals, 1 represents the bottom board of a wagon-box, and 2 the side-board. The wagon-box rests upon the bolster 3, to which is attached our improved extension wagon-stake, consisting 30 of the hollow rectangular iron post 4, having the lugs 5, 6, and 7 upon its lower end, by means of which lugs it is attached by bolts to the end of the bolster, as shown in the various views.

35 Operating upon the inside of the post 4 is the extension-piece 8, having the recess 9 in one side near its lower end, and upon its upper end is the cap 10 of such a shape that when said extension-piece is resting upon the 40 bolster inside of the post 4 the cap 10 matches with the top of the post 4 in shape and size, and thus gives the appearance of being one solid stake.

To the outside of the post 4, near the upper 45 end thereof, is attached a leaf-spring 11, the free end of which is bent inwardly through the aperture 12 in the face of said post and presses against the side of the extension-piece 8, then outwardly through said aperture and

50 upwardly, forming a handle for the operation of said spring. When said extension-piece 8 is in its highest position, as shown in Figs. 2 and 3, the free end of the leaf-spring 11 engages in the recess 9 to hold said extension- 55 piece in its position.

We prefer to sink the lower end 13 of the hollow post 4 into the end of the bolster 3, as shown in Fig. 2, and said post is most economically made of cast-iron.

An extension wagon-stake of our improved 60 construction is very inexpensive, strong and convenient to operate, and possesses numerous advantages over the stakes heretofore in use.

We claim—

65 The combination with a bolster or rocker of a wagon, of an extension wagon-stake consisting of the hollow rectangular post 4 having its lower end 13 sunk into the end of the bolster or rocker and having the aperture 12 70 in one of its side faces and communicating with its interior opening, the lug 5 projecting outwardly at right angles from near the lower end of said post and resting on top of the bolster or rocker, the lugs 6 and 7 projecting 75 downwardly and inwardly from near the lower end of said post and engaging one on each side of the bolster or rocker, said post 4 and the lugs 5, 6 and 7 being cast integral, the bolt passing horizontally through the lugs 6 80 and 7 and through the bolster or rocker, the bolt passing vertically through the lug 5 and through the end of the bolster or rocker, the cast extension-piece 8 slidingly positioned within the hollow of said post 4 and having 85 the recess 9 in its face and near its lower end, the cap 10 formed integral with the upper end of said extension-piece, said cap being of such a shape and size that when said extension-piece is resting in its lowermost position 90 within the hollow of the post 4, said cap matches with the top of said post 4 in shape and size, the leaf-spring 11 attached to the outside of the post 4 and having its free end bent inwardly through the aperture 12 95 in said post and engaging the extension-piece 8, and then outwardly through said aperture and upwardly forming a handle for the operation of said spring, substantially as specified.

100 In testimony wherof we affix our signatures in presence of two witnesses.

JULIUS G. KERNEK.
HENRY E. KERNEK.

Witnesses:

J. L. CLEVLEN,
J. S. MENGEL.
